FIG. 1.

FIG. 2.

FIG. 3.

FIG. 4.

Inventor
W. Szczerba

By

J. H. Bryant
Attorney.

UNITED STATES PATENT OFFICE.

WALTER SZCZERBA, OF NEWARK, NEW JERSEY.

ENVELOPE.

Application filed May 20, 1922. Serial No. 532,476.

To all whom it may concern:

Be it known that I, WALTER SZCZERBA, a citizen of Poland, residing at Newark, in the county of Essex and State of New Jersey, have invented certain new and useful Improvements in Envelopes, of which the following is a specification.

The present invention relates to envelopes, and has for its principal object the formation of an envelope blank, so constructed for readily permitting the user of the envelope blank to assemble the same whereby a simple and efficient envelope is formed.

A further object of this invention is the formation of an envelope blank being provided with interlocking side and end portions, whereby these side and end portions may be readily engaged with each other for absolutely preventing the opening of the envelope without informing the receiver of such opening or other tampering.

A still further object of this invention is the provision of an envelope wherein the same may be increased in length to receive 25 papers or other mailing matter of a length greater than that of the normal length of the envelope.

With the above general objects in view and others that will appear as the nature of the 30 invention is better understood, the same consists in the novel form, combination and arrangement of parts hereinafter more fully described, shown in the accompanying drawing and claimed.

In the drawing, wherein like reference characters designate corresponding parts throughout the several views,

Figure 1 is a plan view of the envelope blank,

Figure 2 is a similar view with the end flaps of the same engaged,

Figure 3 is also a plan view of the rear side of the envelope showing the same still more fully assembled than is shown in Figure 2, and

Figure 4 is a plan view of the rear side of the envelope, with the side and end flaps being fully assembled.

Referring more in particular to the several views, I have shown an envelope blank comprising a central rectangular section 1 provided with an integral top and bottom flap 2 and 3 of the usual design. The opposite ends of the section 1 are also provided

with flaps 4 and 5, and the top and bottom and end flaps are creased at their edges adjacent the central section 1 as shown in Figures 1, 2 and 3 whereby the four flaps may be folded inwardly upon themselves so as to lie adjacent the inner face of the rectangular section 1. The outer edges of the flaps 2 and 3 are provided with a suitable adhesive 6 such as glue or the like and the upper flap 2 is provided with a central inwardly projecting slit 7 for providing the section 2 with a small tongue 8 when the same is creased or bent upon the line X—X as shown in Figures 1, 2 and 3. The bottom flap 3 is also slit as at 9 for forming a small tongue 10 upon the flap 3 when the same is bent or creased upon the lines Y—Y. The longitudinal axis of the slit 9 in the flap 3 is oblique to the longitudinal axis of the slit 7 in the flap 2, whereby when the upper and lower flaps are joined together as shown in Figure 4, the inner edge of the flap 8 will overlie the adjacent inner edge of the flap 10 for purposes readily apparent.

As previously noted, the rectangular section 1 is provided with end flaps 4 and 5, and each of these flaps are provided with a relatively short projecting tongue 11. These tongues 11 are upon opposite sides of the flaps 4 and 5, and each flap is provided with an inwardly projecting slit. The flaps 4 and 5 may be readily interlocked as shown in Figure 2 and for allowing each opposite tongue 11 to underlie the adjacent end flap of the section 1, these tongues 11 may be secured to the under surface of the adjacent end flaps by applying to the said surface of these flaps an adhesive 13.

In the preferred embodiment of my invention, the envelopes are sold to the public in the blank form shown in Figure 1 with the top and bottom and end flaps unfolded. From the above description it will be readily seen that anyone desiring to use my type of envelope will first fold the end flaps 4 and 5 inwardly upon the inner face of the rectangular strip 1 and by inserting the tongues 11 beneath the edges of each adjacent flap the end members are securely held together and especially when the adhesive 13 is moistened for rigidly joining these projecting tongues beneath each opposite flap 4 and 5. This procedure is clearly shown in Figure 2. If it should so happen that the

articles to be received within my envelope are of a length greater than the length of the rectangular strip 1, the end flaps 4 and 5 may be so folded to compensate for this increased length. The bottom flap 3 is then folded over upon the side flaps 4 and 5 and secured thereto by the adhesive 6. The tongue 10 on this flap is not adhesively secured to the adjacent face of the flap 4 but the same is folded backwardly upon the line Y—Y as shown in Figure 3. After placing the letter or similar article within the envelope formed as in Figure 3, the upper flap 2 is then folded over upon the back 15 of the envelope and the end of this flap adjacent the tongue 8 is placed alongside of the slit 9 within the lower flap 3. The tongue 8 of the upper flap 2 is then bent backwardly upon its line X—X and after this 20 tongue has been so bent the tongue 10 of the lower flap 3 is then secured by its adhesive 13 to the adjacent face of the upper flap 2 and after this has been accomplished the tongue 8 is then folded backwardly upon 25 its line X—X to be adhesively secured to the adjacent face of the lower flap 3. After the side and end flaps are folded upon the rectangular strip 1 the envelope will assume an aspect as clearly shown in Figure 4.

30 While there is herein shown and described the preferred embodiments of the present invention it is nevertheless to be understood that minor changes may be made therein without departing from the spirit and scope 35 thereof.

Having thus fully described the invention, what I claim as new is:—

1. In an envelope of the type described, a central rectangular strip defining the front face thereof, foldable side flaps integrally joined to the central rectangular strip, a tongue projecting outwardly from each side flap and said flaps being longitudinally slit 40 at one side of the tongue adapted for interlocking engagement with each other, other integral flaps carried by the upper and lower ends of the said central strip and adapted to be folded backwardly upon the beforementioned side flaps and locking tongues carried by said flaps for securely retaining the flaps in interlocked engagement. 45

2. In an envelope of the type described, a central rectangular strip forming the front face of the envelope, end flaps integrally carried by said strip and adapted to be folded upon one face thereof, a projecting tongue carried by each flap with each flap slit 55 at one side of the tongue and adapted to be permanently secured beneath each of the opposite flaps and central flaps also carried by the said rectangular strip, one of the central flaps having a slit arranged coincident to the transverse axis of the central strip and the other central flap having a slit disposed at an angle to the transverse axis of the central strip and the slitted portions of the central flaps adapted for interlocking engagement when folded. 60

In testimony whereof I affix my signature.
WALTER SZCZERBA.
